John F. Wellekens, New York, N.Y., assignor to Sonic Dynamics, Inc., Staten Island, N.Y., a corporation of New York

Filed Jan. 27, 1959, Ser. No. 789,378

2 Claims. (Cl. 70—339)

This invention relates to locks, and more particularly to door locks of the character adapted for use in hotels, motels, trains, ships or other places where a change of occupancy often takes place or where a change of combination of a lock is required. It is one of the objects of the invention to provide a lock and key-operating means therefor by which the combination of the lock can be readily changed after an occupant has relinquished the room.

It is well known that occupants of hotel rooms often carry off the key to the doors of the rooms, and while this practice is usually due to absent-mindedness on the part of the hotel guest, there are instances where the key is deliberately appropriated by a thief with the intention of subsequently returning to the room and pilfering the property of a later occupant.

The present invention contemplates a lock which can have its combination or the arrangement of its operative parts quickly altered to thereby prevent the use of the same key after a guest has vacated the room, so that his appropriation of the key will, in the event that his purpose is a nefarious one, avail him nothing. It can, in fact, permit hotel guests to keep their keys as souvenirs of their visit.

It is an object of the invention to provide a lock of the above-mentioned kind in which alteration of the relationship of the operative parts of the lock can be had by the simple use of a secondary, supplement or so-called "combination key" inserted in the lock, for example by the chamber maid after the room is vacated, and which lock can thereafter be operated only by the use of a key that is a mate or companion to the combination key employed for producing the alteration of the combination of the lock.

It is a further object of the invention to provide a lock of the character above described and with which the relationship of the operating parts of the lock can be changed to require a different key, without necessitating the dismantling of the lock.

More particularly, the invention contemplates the provision of a door lock operated in the normal way by the insertion of a key from the outer side of the door and regulated as to the co-operative relationship of its key-receptive parts by a supplemental non-rotative key inserted in the lock from the inner side of the door and maintained in the lock. By the use of such a supplemental key, the lock can be adapted to require it to need an operating key of different contour than the first key to enable it to be opened.

With these and other objects to be hereinafter set forth in view, I have devised the arrangement of parts to be described and more particularly pointed out in the claims appended hereto.

In the accompanying drawings, wherein an illustrative embodiment of the invention is disclosed

Fig. 1 is a vertical sectional view through a lock constructed according to the invention;

Fig. 2 is a top plan view of the lock cylinder;

2

Fig. 3 is a front elevational view of the cylinder; Fig. 4 is a side elevational view of the cylinder, showing the tumbler plates in position in it;

Fig. 5 is a face view of one of the tumbler plates; Fig. 6 is a face view of one of the stop plates, showing its relationship to the cylinder and tumbler plates;

Fig. 7 is a rear view of the lock;

Fig. 8 is a sectional view, taken substantially on the line 8—8 of Fig. 6, looking in the direction of the arrows; and

Fig. 9 is a face view of one of the stop-plate separators.

Referring to the drawings, 1 indicates the lock housing which is provided at the rear with a closure plate 2, secured at the back of the housing by the screws 3a.

15 The rotative cylinder of the lock is indicated at 3, the same being provided with an axially-extending key-hole 15, and also formed with a plurality of similar, equally-spaced slots 4 extending transversely through it. Mounted for vertical sliding movement through the slots 4 are 20 the tumbler plates 5, the shape of each of these plates being clearly seen in Figs. 5 and 6. Each of the plates 5 is formed with a key-hole 6 and at the upper and lower ends of the key-hole are provided rollers 7 and the same facilitate the entry of the key 10 and reduce wear on the 25 same.

The key shown at 10 in Fig. 1 is that employed for sliding back the bolt of the lock, by the insertion of the key in the key-holes 16 and 6 and on turning the key in the lock in the known manner, thereby causing rotative movement of the cylinder 3 and of the bolt-actuating lever 12 extending through one of the slots 4 in the cylinder 3. Said lever 12 is formed with a foot portion 13 which engages against and retracts the lock bolt by engagement against the part 40 thereof (Fig. 7) in 30 known manner when the cylinder 3 is rotatively moved. The bolt of the lock is spring-biased to normally projected or locked position.

The various tumbler plates 5, as well as the bolt-retracting lever 12 are maintained against movement out of the 40 slots 4 and resultant separation from the cylinder 3, by means of a pin 14 extending longitudinally through the cylinder for the greater part of its length and engaging in a notch 9 provided in one edge of each of the tumbler plates 5 and similarly provided in an edge of the bolt-operating lever 12.

The ability of the cylinder 3 to rotatively move in a manner to swing the lever 12 to actuate the bolt of the lock, is dependent upon the positioning of a plurality of 50 stop-plates 18, one of which is shown in detail in Figs. 6 and 8. These stop-plates are located within the housing 1 in position between the tumbler plates 5, and by means of the key shown at 19 in Fig. 1, or any one of a number of keys of different contours, the stop plates can be positioned in various ways or combinations, each 55 arrangement of these stop plates requiring a lock-operating key of a certain contour to position the tumbler plates in the manner permitted by the stop plates and required to enable the cylinder to be rotatively moved.

As shown in Fig. 6, each stop plate 18 is provided with 60 an aperture 20 encircling the cylinder 3 and within which the cylinder 3 may be rotatively moved by the turning of the key 10 as long as a suitable non-rotative key 19, herein referred to as the "combination key" remains in place in the lock. Each of the stop plates 18 is provided with 65 a pair of laterally-projection lugs 21, which lugs are, in the locked position of the lock, disposed in the path of movement of shoulders 8 formed on the spurs 23 provided on the tumbler plates 5.

The several stop plates 18 are mounted for vertical raising and lowering sliding movements within the housing 1, upon pins 24 (Fig. 6) which pins extend from the front 70 of the housing 1 to enter its back plate 2. The pins 24

pass through slots 25 formed in the stop plates 18 and the stop plates may thus be slid up and down to an extent permitted by these slots. The stop plates 18 are also each formed with a key-hole 26, provided at the top and bottom with rollers 27.

To maintain the stop plates 18 in their equally-spaced apart relationship, a plurality of fixed separators 28 are provided, one of such elements being shown in Fig. 9. Each of the separators 28 has a key-hole 29 and holes 30, the pins 24 passing through the latter holes and supporting the separators.

The combination key 19 enters through the key-hole 31, located in the rear plate 2 of the housing and extends through the key-holes 26 in the stop plates 18 and has its rear end or finger-piece 19a located in a recess or depression 32 in the rear plate 2, so that this portion of the key 19 may, if desired, be covered or concealed by a suitable closure for the recess 32, and thus rendered accessible for removal only by an authorized person. Since a combination key such as that shown at 19, or one of another contour, is not rotative in the lock and must remain in the lock in order to enable the lock to be operated by a companion key 10, it is desirable that the combination key 19 be accessible only to a person authorized to alter the operating characteristics of the lock.

From the foregoing, the structure and operation of the lock will be readily understood. Many combination keys, all having the same general cross-sectional shape but differing in contour, may be used in place of that shown at 19, and each of such keys requires suitably-contoured mating key 10 by which the lock can be operated as long as the companion combination key remains in place in the lock. For example, when a tenant vacates a room and carries off the door key, the chamber maid removes the combination key 19 which was the mate to that carried off. She then inserts a combination key 19 of a different contour from that which she removed, and such insertion of the new combination key elevates and lowers the several stop plates 18 to new positions thus interposing the lugs 21 in the path of rotative movement of the tumbler plates and requiring suitable raising or lowering movements of the tumbler plates by the insertion of a new key 10 that is a companion to the combination key that has just been inserted in the lock. As long as the particular combination key so inserted remains in the lock, the stop plates 18 controlled by that key, will occupy certain specific positions so that their lugs 21 can be cleared by movement of the tumbler plates 5 to specific positions, as determined by the insertion of a companion key 10 in the lock.

It will thus be apparent that the operation of the lock is controlled by two keys, one of which remains in the lock and determines the combination, and the other operates the bolt-retracting means, and which it will continue to do as long as the first key remains in the lock. When the first key is removed, and another key of a different contour is substituted for it, a new key, companion to the substituted combination key, must be used to operate the lock. This requires merely the removal of one combination key from the lock and the insertion of a combination key of a different contour to secure a change of the combination of the lock.

Having described a single embodiment of the inven-

tion, it is obvious that the same is not to be restricted thereto, but is broad enough to cover all structures coming within the scope of the annexed claims.

What I claim is:

- 5 1. A lock having a casing, a cylinder mounted for rotative movement, a bolt-operating element, the cylinder being coupled to the bolt-operating element in a manner to cause retracting movement of the bolt operated by said element upon rotative movement of the cylinder, the cylinder having a plurality of slots extending through it, tumbler plates extending through the slots and having projecting spurs provided with shoulders, the tumbler plates having key-hole openings, the cylinder having a key-hole opening, a bolt-operating key extendable through the key-hole openings in the tumbler plates and cylinder and adapted by its shape to cause selective projection of the spurs beyond the periphery of the cylinder, a plurality of slidable stop plates contained in the casing and adjustable toward the tumbler plates, each of the stop plates being provided at one end with a lug for positioning in the path of movement of one of the spurs, the casing and the stop plates having key-hole openings, and a non-rotative combination key inserted through said key-hole openings to thereby selectively locate the stop plates 10 with their lugs in blocking position for the tumbler plates 15 unless the stop plates and tumbler plates are complementarily positioned by the use of the combination key.
- 20 2. A lock having a casing, a cylinder mounted for rotative movement therein, a bolt-operating element, the cylinder being coupled to the bolt-operating element in a manner to cause retracting movement of the bolt operated by said element upon rotative movement of the cylinder, the cylinder having a plurality of spaced slots extending transversely through it, tumbler plates fitted 25 in the slots and slidable therein, each of the tumbler plates having a pair of radially projecting spurs forming shoulders, the tumbler plates having key-hole openings, the cylinder having a key-hole opening, a bolt-operating key extendable through the key-hole openings in the tumbler plates and cylinder and adapted by its shape to cause selective projection of the spurs beyond the periphery of the cylinder, a plurality of slidable stop plates contained in the casing and adjustable toward the tumbler plates, each of the stop plates having an opening 30 extending through it, said openings encircling the tumbler plates, each stop plate being provided with a pair of lugs positioned respectively above and below the tumbler plates and arranged for positioning in the path of movement of one of the spurs, the casing and the stop plates having key-hole openings, and a non-rotative combination key inserted through said key-hole openings to thereby selectively locate the stop plates with their lugs in blocking position for the tumbler plates unless the stop plates and tumbler plates are complementarily positioned 35 unless the stop plates and tumbler plates are complementarily positioned by the use of the combination key.
